UNITED STATES PATENT OFFICE.

BERNHARD SCHNITZLER, OF NEW YORK, N. Y.

ROOFING TILE.

Application filed October 31, 1922. Serial No. 593,165.

To all whom it may concern:

Be it known that I, BERNHARD SCHNITZLER, a citizen of the United States, and a resident of the city of New York, Edgemere, 5 borough of Queens, in the county of Queens and State of New York, have invented new and useful Improvements in Roofing Tiles, of which the following is a full, clear, and exact description.

10 This invention relates to improvements in tiles primarily designed for roofing.

The general object of this invention is the provision of a cheap, simple and durable tile for roofing so constructed as to include 15 all the necessary members for building a complete weatherproof roof by assembling the tiles in position on the roof frame.

This object is accomplished by forming a tile including a body, the lower edge of 20 which is thicker than the upper edge, notching one side of the body so that it will receive projections formed on the side of an adjacent tile, providing on the side opposite the notched side projections for engaging 25 in the notches of an adjacent tile, forming integral with the body a strip which extends over the notched side so as to overlap an adjacent tile, and forming in the lower portion of the tile a hollow member for seating 30 over the strip formed on any tile. In case the tile is to be used for changing the plane of the roof the body is made triangular in shape and with a V-shaped cross section. The remainder of the structure is similar. 35 This and other objects of the invention will be more clearly understood from the following detailed description and accompanying drawings.

Figure 1 is a top plan view of three 40 tiles assembled;

Figure 2 is a section along the line 2-2, Figure 1;

Figure 3 is an elevation of the lower end of a tile;

45 Figure 4 is a top plan view of a tile for changing the plane of the roof;

Figure 5 is an elevation of the lower end of the tile shown in Figure 4;

50 Figure 6 is a top plan view of a portion of a roof formed by assembling a number of tiles.

Referring to the above mentioned drawings, the invention includes a rectangular body 11, one side of which has a plurality of notches 12 formed therein, and the other side of which has a plurality of projections

13 formed thereon. The projections 13 formed on one side of a tile are so shaped and located that they will fit into the notches 12 of an adjacent tile when the ends of the 60 tiles are in alinement with one another. Formed integral with the body 11 and extending over the notched side of the body is a strip 14. In this particular case the strip is of semicircular cross section and is 65 so located relative to the tile that the lower face is a continuation of the top plane of the body 11. The lower end 15 of the body 11 is thicker than the upper end 16, and the tile is gradually tapered from the lower end 70 to the upper end. A member 18 is formed integral with the lower portion of the body, providing a pocket 17 into which the upper end of the strip 14 may be fitted. If a member 18 were not formed providing a pocket 75 17 and a pocket were formed separately in the tile, the thickness of the material in the tile above the pocket would not be sufficient to withstand the strains that might be exerted upon it. Consequently, a large number of the tiles would be destroyed by breaking. 80 Cast with the body of each tile is a flexible strap 19 provided for attaching the tile to the cross members 10 of the roof structure, as shown in Figure 2. Referring to Figure 4, the body 11 of the tile is made of a somewhat triangular shape presenting a V-shaped cross section, as seen in Figure 5. The sides are provided with the projections 13 and the notches 12 as described 85 above. The strip 14 is also formed integral with the tile for overlapping an adjacent tile so as to cover the joint between them. A reinforcing member 20 extends along the central line of the tile, strengthening it so 90 that it is not likely to break along such line. This tile is used for changing the plane of the roof and is so constructed that the portion to the left of the member 20 would lie in one plane while the portion to the right of the reinforcing member 20 would lie in another plane, thus connecting two rows of 95 tile in different planes.

In order to explain the assembling of the roof, three tiles 21, 22 and 23 are taken. 105 The tiles 21 and 22 are placed on the cross members 10 of the roof frame and the straps 19 attached to said cross members. The projections 13 formed on the tile 22 project into the notches 12 formed in the tile 110 21 when the ends of the tiles are in alinement. The strip 14 carried by the tile 21

overlaps the joint between the tiles 22 and 21. The tile 23 is then placed in position on one of the cross members 10 with the lower edge 15 resting on the upper edges 16 of the tiles 21 and 22. The member 18 which is formed in the central portion of tile 23 and presenting a pocket 17 fits over the upper end of the strip 14 carried by the tile 21. In positioning one tile on the other 10 concrete or cement might be introduced between the bearing edges so that a tight joint would be formed.

Referring to Figure 6, a roof is shown which extends in two different planes. In 15 this case the modified tile shown in Figure 4 is used to fit over the joining edges of the two sections of the roof. The assemblage is similar to that described in the preceding paragraph. The tile shown in Figure 4 may 20 be used in conjunction with sections of a roof extending in two different planes irrespective of whether the sections form an acute angle or an obtuse angle with one another on the outside.

25 A tile of this type would be constructed from concrete or any other suitable material and the forming of it is accomplished preferably by the use of molds. In constructing tiles by the use of concrete they 30 may be colored to suit the purpose for which they are to be used.

I would state in conclusion that while the 35 illustrated example constitutes a practical embodiment of my invention I do not limit myself strictly to the exact details herein 40 illustrated since manifestly the same can be considerably varied without departing from the spirit of the invention as defined in the appended claims.

40 Claims.

1. A roofing tile comprising a body having notches formed in one side, projections shaped to fit the tile notches formed on the other side, a strip formed integral with the 45 body and extending beyond the notched edge, and a member formed in the center of the lower edge of the body for receiving an end of a strip formed integral with a tile.

2. A tile roof including a plurality of 50 rows of tiles having a plurality of tiles in each row, each tile comprising a body having one side notched and the other side provided with a plurality of projections, the notched side being adapted for receiving the 55 projections of an adjacent tile and the projections on the side opposite the notched side being adapted for fitting into the notches of an adjacent tile, a strip formed integral with the body of each tile and extending 60 over the notched side for overlapping the

adjacent tile to cover the joint, and members formed in the lower portion of each tile for fitting over the strip on the tile next below.

3. A tile roof including a roof frame, a 65 plurality of rows of tiles having a plurality of tiles in each row mounted on the roof frame, each tile comprising a body having one side notched and the other side provided with a plurality of projections, the notched side being adapted for receiving the projections of an adjacent tile and the projections on the side opposite the notched side being adapted for fitting into the notches of an adjacent tile, a strip formed integral 70 with each tile and extending over the notched edge for overlapping the adjacent tile, members formed in the lower portion of the tile for fitting over the strip formed integral with the tile next below, and means 75 provided in conjunction with each tile body for attaching it to the roof frame.

4. A tile roof including a roof frame, a 80 plurality of rows of tiles having a plurality of tiles in each row mounted on the roof frame, each tile comprising a body thicker 85 at the lower edge than at the upper edge and gradually tapering from the lower edge to the upper edge, one side of said body being notched and the other side provided 90 with a plurality of projections, the notched side being adapted for receiving the projections of an adjacent tile and the projections on the side opposite the notched side being adapted for fitting into the notches of an adjacent tile, a strip formed integral 95 with the body of each tile and extending over the notched side for overlapping the adjacent tile, members formed in the lower portion of each tile for fitting over the strip on the tile next below, and means cast in 100 the body of each tile for engaging the roof frame to retain the tile in position.

5. In a tile roof of the character described 105 including a plurality of rows of tiles and a plurality of tiles in each row, a tile for changing the plane of the roof including a triangular body having a V-shaped cross section, one edge of said body being notched while the other edge has a plurality of projections formed thereon, said notches serving to receive the projections of the adjacent tile while the projections engage in the notches of the adjacent tile, a strip formed integral with the tile and extending over the notched edge for overlapping the adjacent tile, and a reinforcement formed integral 110 with the tile and extending along its central line.

BERNHARD SCHNITZLER.
